SAFETY LOCK FOR WINDOW SASHES

Emmett A. Barnes, Marietta, Ohio

Application December 23, 1946, Serial No. 718,007

1 Claim. (Cl. 292—63)

1

The present invention relates to a device for locking upper and lower sashes of a window when open and thus preventing the entering of unauthorized persons from the outside.

This safety lock is intended for retaining the two sashes in relative open position whether the top or the bottom sash has been shifted. The device is secured on the inside of the upper sash and consists of a bracket with an upper and a lower hinge lug for engaging a bolt slidable vertically but non-turnable therein, when in locked position.

Objects and advantages of this invention will be found in the subjoined description aided by the attached drawing in which

Figure 1 is a fractional, perspective view of a window partly open and secured by my safety lock;

Figure 2 is a similar view of the window closed and the locking bolt partly displaced either in action of insertion or withdrawal; and

Figure 3 a perspective view similar to Figure 2 but with the locking bolt completely removed.

In the drawing like numerals relate to the same details in the different views.

Reference numeral 10 denotes the upper or outer sash, and numeral 11 the lower or inner sash. On the inner surface of the left side bar of the upper sash 10 is securely fastened, as by screws 12, a bracket 13 provided with a top hinge lug 14 and a bottom hinge lug 15. These lugs are intended to carry in upright position a straight locking bolt 16, having a head 17 at its top and being turned cylindrical at its bottom at 18, as well as at 19 immediately below the head 17. Between these cylindrical portions the bolt is provided with a straight, wedge shaped key or ridge 20. The upper hinge lug 14 has a corresponding V-shaped key-way 21 in its bolt hole, which is of a diameter to fit around the cylindrical neck 19 of the bolt 16. Likewise the tip 18 of the bolt being also cylindrical fits in a round hole 22 of the bottom hinge lug 15. It will thus be seen that the bolt 16 can be turned in both lugs 14 and 15 when fully down in position.

A locking arm 25 has a downturned heel 26 reaching inwardly from the axis of the bolt 16 to contact with top cross bar 27 of the lower sash 11. This locking arm has a boss 28, having a round hole 29 fitting the tip 18 of the bolt 16. The hole 29 has a V-shaped key-way 30 for the key 20 on the bolt 16, thus permitting sliding action between the bolt 16 and the locking arm 25.

2

It will be noted that the length of the cylindrical neck 19 is only slightly more than the thickness of the upper hinge lug 14, while the cylindrical tip 18 must have a length somewhat greater than the added thickness of the lower lug 15 and the arm hub 28. This will permit the turning of the bolt 16 in the lugs 14, 15 and the hub 28 when the parts are assembled and the sashes closed but at no other time, because in any other position of the parts the bolt is prevented from turning by being keyed in the keyway 30 of arm 25, while the latter is prevented from turning by the flat side surface 31 on the arm 25 which abuts against the flat surface 33 of the bracket 13.

In assembling the parts of my safety lock, the bracket 13 is first secured on the upper sash 10 while the window is closed as in Figure 2, thus the arm 25 is placed in position over the lower hinge lug 15 with their holes 22 and 29 in axial alignment. Thereupon the bolt 16 is extended thru the hole 21 of the upper lug 14, care being taken that the key 20 enters the keyway 21, after which the bolt 16 is pushed straight down all the way, in engagement with the lugs 14, 15 and boss 28.

In this position the bolt 16 can be turned so that the key 20 no longer points towards the bracket face 33 but instead in the length direction of the arm 25 so as to register with the key way 30 therein and at the same time locking the top of the key 20 under the lug 14, thus locking the key from withdrawal.

It will now be possible to open the window by either pushing the upper sash 10 down or the lower one 11 up as seen in Figure 1 after having first shifted the locking arm 25 on the rod 16. The heel 26 will then abut against the top bar of the lower sash, thus preventing any further opening of the two sashes.

It is to be understood that the invention as herein disclosed may be varied from the details described and shown without departure from the spirit of the subjoined claim.

45 I claim:

A safety lock for sliding sash windows, comprising a bracket adapted to be secured to a vertical side of the top sash and having two vertically spaced lugs arranged to position over the 50 bottom horizontal rail of the sash, said lugs each having an opening therethrough, the lug openings being vertically aligned, the opening of the top lug having an offset portion, a bolt extending thru the openings of and coupling said lugs, 55 a key extending lengthwise of the bolt and ter-

minating short of each end of the bolt to leave a portion of each end of the bolt of circular form for turning in a lug opening, said key being slideable in the offset portion of the top lug, the circular end portion at each end of the bolt being in a lug opening when the bolt is extended downwardly to the limit of its movement thru the lugs whereby the bolt may be turned to move the top end of the key from alignment with the offset, and a locking arm having a circular opening in one end to receive the bolt, said arm opening having a key way, the arm being of a length to extend from the bolt across the top rail of the lower sash, the arm in its lowest position on the

bolt engaging the circular lower end portion of the bolt whereby the bolt may be turned to locate the lower end of said key over the arm out of line with the arm opening key way.
